(57) **CLAIM**

The ornamental design for novelty globe, as shown and described.

DESCRIPTION

FIG. 1 is a front view of a novelty globe showing my new design;

FIG. 2 is a top-down view thereof;

FIG. 3 is an angled top-down thereof;

FIG. 4 is a left side-facing view thereof;

FIG. 5 is a right side-facing view thereof;

FIG. 6 is a bottom-up view thereof; and,

FIG. 7 is an alternative side-view thereof.

The broken line showing of a stand and the Earth's Equator is included for the illustrative purposes only and forms no part of the claimed design.
